UNITED STATES PATENT OFFICE.

WILLIAM JOSEPH GOING, OF AMSTERDAM, NEW YORK, ASSIGNOR TO KLAUDER-WELDON DYEING MACHINE COMPANY, OF AMSTERDAM, NEW YORK, A CORPORATION OF NEW YORK.

YARN-TREATING MECHANISM.

1,182,164.

Specification of Letters Patent.

Patented May 9, 1916.

Application filed March 11, 1915. Serial No. 13,596.

To all whom it may concern:

Be it known that I, WILLIAM J. GOING, a citizen of the United States, residing at Amsterdam, in the county of Montgomery and State of New York, have invented certain new and useful Improvements in Yarn-Treating Mechanism, of which the following is a full, clear, and exact description, such as will enable others skilled in the art 10 to which it appertains to make and use the same.

My present invention relates to apparatus for treating yarn, and particularly for washing, scouring and dyeing it.

15 It has for its object to overcome some of the difficulties which have arisen in connection with such machines heretofore known to me.

In general, such machines are in the form 20 of rectangular vats containing the various solutions; and several of them are generally used in series, connected together to run from a single source of power, since several solutions are used in treating the yarn to 25 cleanse it, or for dyeing. Usually the yarn is carried through the solution by a pair of aprons running over rolls or sprockets and permitting access of the fluid; the pressure between the two aprons as they run around 30 the sprockets being relied upon to squeeze out the solution from the yarn, so that it is repeatedly squeezed and filled and thus thoroughly cleansed or thoroughly dyed.

For obvious reasons it is impracticable to 35 insure the passing opposite one another of the bars of which the aprons are composed as they progress around the sprockets and often the yarn treated in this way is not uniformly cleansed or dyed. It is also common 40 in such machines to provide squeezing rolls at the end of the machine, or at the end of each one of the series of machines, which are kept together under heavy pressure, so that the yarn will have as much as possible 45 of the liquid squeezed from it. These are usually covered with rubber and when they deteriorate or wear out must be removed

from the machine and sent to experts for recovering. In such machines, also, the 50 yarn is carried through by the aprons without other agitation, and the washing or impregnation with the dyeing solution thus effected is not as thorough as it should be.

These defects of machines as commonly 55 constructed are overcome in my improved apparatus. Herein the aprons consist of sprocket chains running through the tank in several stages, carrying rigid metal bars, which are rubber covered by preference, and run on sprockets; one set of sprockets for 60 each of the aprons is driven, so that the aprons travel at the same speed throughout; the gearing is carried on frames pivoted at one end, and I provide means for oscillating the other end of the frames, so that the 65 aprons carrying the yarn are alternately raised and lowered through the liquid. This movement is counterbalanced to save power. A portion of one apron is arranged horizontally, or approximately so, so as to provide 70 a moving feeding table for the work, located at the entrance of the machine. I also provide a new construction of roller which will be more specifically pointed out hereinafter, and which may be repaired without taking 75 the roll from the machine. In addition, I arrange stopping devices for the prevention of accident in such a way that the acts which are liable to cause accident themselves serve to stop the machine immediately. 80

The accompanying drawings show an embodiment of my invention.

In them,—Figure 1 is a front elevation of a machine of the character described; Fig. 2 is a vertical section through the machine 85 shown in Fig. 1; Fig. 3 is a plan of the sprocket mechanism with some parts shown in section; Fig. 4 is a rear elevation of the machine; Fig. 5 is a detail of the apron; Fig. 6 is a perspective, broken away, of the 90 squeezing rolls; Fig. 7 is a perspective detail of the improved covering for the rolls; Fig. 8 is an enlarged detail of the transfer mechanism from one of the machines to the

next in the series; Fig. 9 is an enlarged detail in perspective of the releasing device for the stopping and starting lever; and Fig. 10 is a detail of part of an apron and 5 roll.

I have applied reference letters with various exponents, each letter referring to special parts of the machine, as will be obvious from the description.

10 Referring to Figs. 1 to 4, A is the frame of the machine, the various shapes of portions of which will be best understood from the drawings, and which may be varied indefinitely in shape according to the detail 15 of the remainder of the apparatus. B is an electric motor driving the apparatus through a gear B¹. A second gear B² is mounted on a countershaft B⁴, as is also a gear B³. The main shaft of the machine is 20 lettered C and is driven by a gear C², meshing with the gear B³, through the collar of a clutch C¹. A worm gear C³ drives the worm wheel E¹ on the shaft E, presently to be referred to, and a gear C⁴, through another gear D¹ on the shaft D and worm D² 25 upon that shaft, drives a worm gear F¹ turning the shaft F. On the right-hand end of the shaft C (Fig. 1) is a bevel gear C⁵ driving another bevel gear G¹, presently to be further described; a clutch C⁶, the collar C⁷ of which is fastened to the shaft, connects the gear C⁵ thereto or throws it out, as 30 may be desired.

Turning now to Fig. 2 in connection with 35 Fig. 1, it will be seen that the apparatus is located in a tank T, and in part consists, as already pointed out in my statement of invention, of two aprons, marked I and J. The construction of these is similar and is 40 indicated in detail in Fig. 5, in which I is the sprocket chain, on the links of which collars I¹ are located which carry metal rods I², with rubber coverings I³. The travel of these aprons is in the direction shown by the 45 arrows thereon, and it will be understood that there is a set of sprockets for each side of each apron or carrier (see Fig. 3), which occupies substantially the width of the tank T. I will first trace the course of the apron 50 J, starting from the entrance to the machine, which is at the upper left-hand side of Fig. 2. A portion of the apron runs substantially horizontally over the sprockets K⁸ and K⁹, then running down to the sprocket K⁶, horizontally at the bottom of the tank 55 to the sprocket K⁵, then over the smaller sprocket K⁴, then to K³, the smaller sprocket K², then meshing with the larger sprocket K¹, which is the driving wheel, upward to 60 the exit of the machine at the sprocket K; and then returning to the bottom of the machine, after delivering the goods therefrom, passes around the sprockets K¹¹ and K¹⁰, back to K⁸. In order to keep a proper ten-

sion upon this apron, it runs over an idler 65 sprocket K⁹, mounted upon an arm P pivoted at p; attached thereto is a rod P¹ and a spring P² secured in usual ways to the rod presses the latter upward and pulls upon the sprocket K⁹, putting a tension upon the 70 apron sufficient to keep it tight.

The apron I, after passing around sprocket L⁷, at the upper left-hand corner, goes downward over the sprockets L⁶, L⁵, L⁴, etc., passing around the driving sprocket 75 L¹ to the exit of the machine at the sprocket L, thence returning to the sprocket L⁷ at the entrance. The tension device for this apron is lettered Q, an arm or lever carrying the sprocket L⁸ at one end; passing through its 80 other branch is a pin Q², around which is a spring Q³; the pin is pivoted to the arm at q¹, and the arm revolves about a pin q² under the pressure of the spring, thus forcing the sprocket L⁸ downward and putting a 85 suitable tension upon the apron I.

The apron J is supported between the sprockets by guide rollers H¹², H¹², etc., which prevent it sagging too much, and stiffen it when it is oscillated, as presently 90 to be described. The sprockets K³, K⁵, L³, L⁵ are carried upon frames, the bars of which are marked H⁹, H¹⁰, and which are pivoted respectively at h⁹, h¹⁰ on the frame A. This is the oscillating device to which 95 I have referred, and which will be understood best from Fig. 2, in connection with Fig. 4. The bevel wheel G¹, on the right-hand side of Fig. 1, drives a shaft G, at the opposite end of which (see the left side of 100 Fig. 4), is a gear G², which revolves another gear G³ upon a stud G⁴. A counterbalance or pendulum H is connected to the gear G³ by a link h¹; the weight H¹ is suitably proportioned to the work to be done, as will be 105 understood, and adjusting means, consisting of holes h, is provided so that the weight may be raised or lowered as desired, a pin in one of the holes h securing it in place. At the upper end of the counterbalance is a partial gear H² meshing with a similar gear H³ on a shaft H⁴. Referring now to Figs. 2 and 3, it will be seen that the shaft H⁴ carries a horizontal bar H⁵ to one end of which 110 is pivoted a link H⁸ extending and pivoted 115 to the frame H¹⁰ carrying the sprocket K⁵, etc.; while the other end of the bar H⁵ carries the link H⁶, attached to a bracket H⁷ upon the frame H⁹ carrying sprocket K³, etc. The operation of this part of the machine 120 is as follows: The gear C⁵ on the right-hand side of Fig. 1 is loose upon the shaft C, the collar C⁷ being keyed to the shaft and constituting one part of a clutch C⁶. When the clutch C⁶ is closed the bevel wheel C⁵ revolves with the shaft C and in turn revolves the bevel wheel G¹, turning the shaft G (see Fig. 4). This turns the gear G², and 125

gear G^3 revolves, thus oscillating the counterbalance H , and through the gears H^2 , H^3 rocking the shaft H^4 ; the result of this motion is that the link H^8 is drawn upward as the link H^6 is pressed down, so that the two frames carrying the aprons are first pressed together and then separated; the yarn which is carried between them, as presently to be explained, is first squeezed and then the pressure is released, so that the yarn again absorbs the liquid in the vat. By changing the gears G^2 , G^3 the speed of this movement relative to the travel of the aprons may readily be controlled, and by altering, if desired, the distance of the crank pin from the center on the gear G^3 by means well understood and which it is unnecessary to illustrate or describe, the extent of the oscillation may also be determined.

Referring now to Fig. 2, an important and valuable feature of the machine is found in the rolls W , W on the same shaft as and turned by the sprockets L^2 , L^4 , on the left side of the machine. A detail of the operation of this part of the apparatus is found in Fig. 10.

It will be seen that the apron I passes around these rolls, and as it does so carries with it the skeins of yarn X to be treated. This action prevents the skeins bunching in the opening between the aprons caused by the separation of the sprockets L^4 , K^4 , L^2 , K^2 , respectively; the space between the roll W and the apron J , carried by the sprockets K^4 , etc., being so short that the skeins are certainly transferred to the apron J , without any opportunity to become bunched. At the same time the passage of the apron around the roll squeezes the skeins so that most of the solution is pressed out of them, and as they are released from this pressure and pass through the opening between the roll and the apron J , they again absorb the solution; this action tends to cause them to be thoroughly impregnated with whatever solution may be in the tank.

The yarn passes into the machine from the table N , on the left-hand side of Fig. 2, and leaves it on the right-hand side as the apron passes over the sprocket K (see Figs. 2 and 3). Upon leaving the apron at the sprocket K , it passes from the machine between the squeezing rolls. These latter are shown in Fig. 6 with their driving gear, and in Fig. 7 as to their construction. Referring to Fig. 6, the rolls F^4 , F^5 are driven from the worm gear F^1 through the shaft F , the upper roll being turned by the gear F^3 , taking its motion from the gear F^2 . The lower roll has a stationary bearing, but the upper roll has sliding box bearings, as will be obvious, and is forced down by levers F^6 , F^7 , only one of which is shown, the other being partly broken away for clearness of illustration;

these levers have lugs f^2 which press down the sliding boxes of the rollers F^5 by springs F^8 secured to rods F^7 pivoted at f^1 in the frame A and bearing upon the eye in the end of the lever F^6 . A nut and lock nut F^9 determine the tension of the spring.

The construction of the rolls is indicated in Fig. 7. A slot is cut in the metal roll F^5 , for example, and in this slot is secured, by means of a rod F^{15} of wood, the end of a suitable textile material. The machine is then allowed to operate and the roll rotates until a sufficient thickness of the material, in the judgment of the operator, is formed upon it, when the end is cut off. No securing means for the end is ordinarily necessary, because when the wet yarn is squeezed the whole covering becomes soaked with the liquid and the end remains in place. The material which I have used and prefer is sail cloth or canvas, since I find that when it gets wet, it is soft enough not to injure the yarn, and yet it has sufficient bite to grip it and carry it through the rolls easily. As will be manifest, it will not be necessary to remove the rolls from the machines for recovering, since the old covering may be cut off from them and the stick F^{15} can be pulled out, or be driven out from one end and be removed by a few taps of a hammer.

At the entrance to the machine there is a feeding roll R , geared by gears R^1 , R^2 to the sprocket K^7 (see Figs. 2 and 4), which insures the certain delivery of the yarn to the opening between the aprons I and J .

The roll R seems at first sight to be unnecessary, because the action of the conveyer J , where it passes horizontally into the machine, carries the skeins of yarn to the opening between the aprons; but this is not so, because the roll straightens out the skeins, which in practice are liable to curl up, and prevents their being thrust back when they strike the apron I as it passes downward into the machine. In practice, there is not sufficient adhesion of the yarn to the traveling conveyer to prevent this occurring, and the skeins are thus apt to become tangled or displaced, not passing through the solution evenly as they should. The gears upon this roll and the shaft of the sprocket beneath it are necessary, in order to give the roll the proper direction of motion.

Referring now to Figs. 2 and 8, I show the mechanism which is used when a plurality of the machines is coupled together. Extensions A^1 of the upper part of the machine register with the outside of the vat T^1 of a second machine. From the shaft F , by means of a sprocket, is driven a transfer roller F^{13} , carrying the yarn to the apron J^1 of a second machine, as shown especially

in Fig. 8. The yarn being brought up from the first vat on the apron J is transmitted to the squeezing rolls, and is then carried to the transfer roll F¹³, which in turn drops it upon the apron J¹ upon the succeeding machine.

The transfer roll F¹³ is a desirable feature of the machine. By arranging the aprons in horizontal stages in the way which I have shown, and by oscillating them, so that the solution in the tank is caused to impregnate them very thoroughly, I am enabled to make substantial savings in floor space by shortening the machines; but it becomes necessary in doing this to bring the aprons to the squeezing roll at the end of the machine, at an angle greater than in those forms of apparatus in which a larger floor space is taken so as to accommodate a long apron. As the goods pass through the squeezing rolls F⁴, F⁵, they would have some distance to fall to the apron or carrier of the next succeeding tank and might not always reach the proper place to enter the machine with certainty. The transfer roll obviates this difficulty and carries them directly to the desired position. To adjust it to the desired relation between the squeezing rolls and the apron of the next tank, it is provided with slotted supports, in which its bearing may be moved about the center of the shaft F.

As these machines are driven by power and the load upon them varies considerably, an ample surplus of power must be provided; and as the squeezing rolls are under very heavy pressure, any operation about the machines is dangerous unless abundant facilities for stopping them quickly be provided. This I have arranged in the apparatus herein illustrated.

Referring to Figs. 1, 4 and 9, the stopping system bears, in general, the reference character M, with various exponents. In Fig. 1 the lever M is an ordinary shifting lever working through the link M¹⁰, the lever M¹¹, pivoted at m³ and operating the collar of the clutch C¹, connecting the gear C² to the shaft C. A spring M⁹ of ample power to throw the lever is connected to the link M¹⁰ and as a factor of safety another spring M⁸ is also provided, so that when the lever M is released, it will certainly be operated. The lever M is held in place by a cam M¹ formed upon a gear M². A notch behind the cam holds the lever M in place, but when the gear M² is revolved by moving the handle M⁴, the inclined surface of the cam is presented to the lever M; the springs M⁷, M⁹ pull over the lever and shift the clutch C¹, bringing the machine to an instantaneous stop, inasmuch as the worm gears C³, D² serve as effective brakes. So much is old and common, but the improved arrangements next to be described I believe

to be new with me. At M⁶ (see Figs. 1 and 4) is a board M⁶ mounted rigidly upon a shaft m²; connected to the shaft at each end is a bell crank lever M⁵. On the side of the machine is a bar M¹⁸, connected at one end to the lever M⁴ and sliding in a guide m¹, a stop m limiting its movement. One of the bell crank levers M⁵ connects with this bar at a slotted end m⁵. It will be obvious that if the hand is thrust against the board M⁶ with sufficient force to make it likely to get entangled in the machine, the lever M⁵ will, by the rotation of the shaft m², be thrown to the right in Fig. 1, throwing with it the bar M¹⁸ and thus operating the lever M⁴, turning the cam M¹ so as to release the lever M, and throwing out the main clutch of the machine. On the other side of the machine the corresponding bell crank lever M⁵ is connected to a sliding bar M¹⁵, to which are also connected the handles M¹⁴, M¹², the latter working against a spring M¹³. At the left-hand end of the bar M¹⁵ (see Fig. 4) is a lever M¹⁶ and a board M¹⁷ (see Fig. 2) is connected to the shaft to which this lever is keyed. This board, as will be observed, is in front of the rollers F⁴, F⁵, which squeeze the yarn, and it will be obvious from the connections that if this board be pressed toward the rolls, it will throw the bar M¹⁵ to the right and operate the bell crank lever M⁵, thus, as already explained, throwing out the main clutch of the machine.

In Fig. 4 the steam pipe S shows a source of heat for the fluid, while in Fig. 1 a valve V, operated by the pedal V³ through means of the bar V² and a bell crank lever V¹, serves to drain off the liquid from the vat when this is desired.

Having described my invention, what I claim as new and desire to secure by Letters Patent is:

1. In a machine for treating yarn in the skein, the combination of a tank, aprons, and driving mechanism therefor for carrying the yarn through the tank, with means for oscillating the aprons.

2. In a yarn treating machine, the combination of a pair of aprons running in substantially parallel lines, driving mechanism for the aprons, and means for oscillating the aprons, such means approximating one part of the aprons to another part thereof, and then separating them; in combination with a tank wherein the aprons are placed so that the yarn is carried through the tank and agitated while therein.

3. In a yarn treating mechanism, the combination of a pair of traveling aprons with mechanism for causing them to travel in approximately parallel planes, a tank, and oscillating mechanism for the aprons; at least one of the aprons having a substan-

tially horizontal portion adjacent to the entrance between them, serving as a conveyer for the material to be treated.

4. In a yarn treating machine, the combination of a tank, aprons composed of sprocket chains and bars extending between the chains, driving sprockets for each of the aprons, and loose sprockets disposed to carry the aprons through the tank in substantially parallel planes, the loose sprockets being of different diameters.

5. In a yarn treating machine, the combination of a tank and a pair of aprons, each composed of two sprocket chains with connecting rubber-covered bars horizontally extending between the chains, with means for driving the aprons so as to cause them to pass through the tank.

6. In a yarn treating machine, the combination of a tank containing a solution, a pair of aprons composed of sprocket chains with horizontal rubber-covered bars extending between them, the aprons supported in superposed planes substantially parallel; with oscillating means arranged to approximate portions of the aprons to one another at one part of the oscillation and to separate them at another part thereof.

7. In a yarn treating machine, the combination of a tank containing a solution, a pair of aprons traveling through the tank in substantially parallel planes, each apron composed of a pair of sprocket chains with horizontal rubber-covered bars extending between them, driving sprockets for the aprons and loose sprockets supported upon frames, such loose sprockets also carrying the aprons, with oscillating means for the frames; whereby the frames are caused to oscillate and thus agitate the aprons in the solution, as described.

8. In a yarn treating machine, the combination of a tank containing a solution, a pair of aprons traveling in substantially parallel planes in the tank, means for driving the aprons, oscillating means for causing them to agitate the conveyed material in the solution, and a counter-balance connected to such oscillating means.

9. In a yarn treating machine, the combination of a tank containing a solution, a pair of aprons traveling in substantially parallel planes in the tank, means for driving the aprons, oscillating means for causing them to agitate the conveyed material in the solution, and a counter-balance connected to such oscillating means, the counter-balance being adjustable so that different momentum effects may be obtained.

10. In a yarn treating machine, the combination of a tank containing a solution, a pair of aprons traveling in substantially parallel planes in the tank, means for driving the aprons, oscillating means for caus-

ing them to agitate the material in the solution, and a counter-balance connected to such oscillating means, the counter-balance being adjustable for weight and stroke, so that the effect of the oscillating means may be varied as desired.

11. In a yarn treating machine, the combination of a pair of aprons, a tank containing a solution, and means for driving the aprons through the tank; with tension devices arranged to keep the aprons under tension.

12. In a yarn treating machine, the combination of a tank containing a solution, a pair of aprons traveling through the tank in substantially parallel planes, driving means for the aprons, and oscillating mechanism therefor; with tension devices arranged to keep the aprons under suitable tension.

13. In a yarn treating machine, the combination of a tank containing a solution, a pair of aprons, each composed of sprocket chains with horizontal bars extending between them, means for driving the aprons through the tank in substantially parallel planes, and tension devices acting upon the sprocket chains so as to keep the aprons taut.

14. In a yarn treating machine, the combination of aprons running through the machine in substantially parallel lines, and a tank containing a solution, the aprons consisting of sprocket chains and connecting bars extending between them with driving mechanism for the aprons comprising driving sprockets and loose sprockets arranged to dispose the aprons in stages within the tank.

15. In a yarn treating machine, the combination of a tank containing a solution, a pair of aprons disposed in several stages in the tank, the aprons composed of sprocket chains and connecting members, driving sprockets for the chains, and loose sprockets, the loose sprockets carried upon frames, with means for oscillating the frames; whereby the aprons are agitated within the solution.

16. In a yarn treating machine, the combination of a tank containing a solution, aprons running through the tank and disposed in substantially horizontal stages therein, the aprons composed of sprocket chains with members extending between them, driving sprockets for the aprons, and loose sprockets carried upon frames, with oscillating mechanism for the frames, the oscillating mechanism approximating the frames at one part of its stroke and separating them at another.

17. In a yarn treating machine, the combination of a tank containing a solution, aprons running in substantially parallel planes through the tank, the aprons com-

posed of sprocket chains with bars extending between them, driving sprockets for the aprons and loose sprockets mounted upon frames, with oscillating means for the frames, and supporting rollers for the aprons arranged at intermediate points upon the frames so as to support the aprons in the spans between the sprockets.

18. In a yarn treating machine, the combination of a tank containing a solution, aprons composed of sprocket chains and bars extending between them, driving sprockets for the aprons, and loose sprockets supporting the aprons in substantially horizontal planes within the tank, a part of one of the aprons being in a substantially horizontal plane adjacent to the entrance of the machine so as to form a feeding table by which material may be introduced between the aprons to be carried through the tank.

19. In a yarn treating machine, the combination of a tank with aprons composed of sprocket chains and connecting members, driving sprockets for the aprons and loose sprockets, frames carrying the loose sprockets, oscillating means for the frames, and tension devices for keeping the aprons taut.

20. In a yarn treating machine, the combination of a tank containing a solution, aprons composed of sprocket chains and connecting members, driving sprockets for the aprons, loose sprockets arranged upon frames, oscillating means for the frames, and tension devices composed of sprockets and springs pressing the sprockets against the aprons so as to maintain them under tension.

21. In a yarn treating machine, the combination of a tank containing a solution, aprons running through the tank disposed in substantially horizontal stages therein, driving mechanism for the aprons, supporting mechanism for the aprons, and means for oscillating said supporting mechanism so that the aprons will be agitated within the tank.

22. In a yarn treating machine, the combination of a tank containing a solution, aprons running in substantially parallel planes through the tank in stages arranged substantially horizontally, driving mechanism for the aprons, supporting mechanism for the aprons, and means for oscillating the supporting mechanism, such means acting to approximate the horizontal stages and then to separate them, so that the material carried upon the aprons may be agitated by oscillation within the solution.

23. In a yarn treating machine, the combination of a tank and a solution therein, aprons running in substantially parallel planes through the tank and arranged in several stages approximately horizontal therein, frames supporting the aprons and

pivoted at one end, oscillating means for the frames approximating the aprons at one part of the stroke and separating them at another so that the material carried thereby is agitated in the solution, a pendulum geared to such oscillating means and constituting a counter-balance therefor, means for adjusting the stroke of the pendulum, thereby adjusting the extent of the oscillation, and means for adjusting the leverage of the pendulum and thereby adjusting the extent of the counter-balancing.

24. In a yarn treating machine, the combination with aprons traveling in substantially parallel planes through the machine, of an opening between the aprons through which the material will pass while being treated, and a roller filling said opening so as to prevent the material bunching therein, the roller feeding the material past the opening to a point where the aprons may engage it again.

25. In a yarn treating machine, a tank containing a solution, a pair of aprons running through the tank in substantially parallel planes arranged in superposed stages, driving means for the aprons, supports for the aprons arranged to leave openings between them at each stage, and rollers filling the openings, one of the aprons passing around the rollers and the other being supported apart therefrom; whereby materials to be treated by the machine are carried around the rollers by one of the aprons, thus squeezing out the solution, and are then passed on to be reengaged by the aprons, as described.

26. In a yarn treating machine, the combination of aprons, a tank and a solution therein, and oscillating means for the aprons, with a pendulum geared to such oscillating means and forming a counter-balance therefor.

27. The combination with a plurality of yarn treating machines comprising tanks, aprons and means for driving the aprons through the tanks, of squeezing rolls at the exit of one machine, a feeding table upon another machine arranged adjacent to the squeezing rolls, and transfer mechanism between the squeezing rolls and the apron of the second machine, as described.

28. The combination with a plurality of yarn treating machines comprising tanks, aprons and driving means for carrying the aprons through the tanks, of squeezing rolls at the exit of one of the machines, a feed at the entrance of another machine arranged adjacent to the squeezing rolls, and a transfer roller taking the material to be treated from the squeezing rolls of one machine to the feed at the entrance of the other.

29. The combination with a plurality of yarn treating machines comprising tanks,

aprons and driving means for carrying the aprons through the tanks, of squeezing rolls at the exit of one of the machines, a feed at the entrance of another machine arranged 5 adjacent to the squeezing rolls, and an adjustable transfer roller taking the material to be treated from the squeezing rolls of one machine to the feed at the entrance of the other.

10 30. Feeding means for a yarn treating machine comprising a tank, aprons and driving means for carrying the aprons through

the tank, such means consisting of a portion of the apron disposed substantially horizontally at the entrance of the machine and 15 traveling toward the machine, with a roller arranged above such horizontal portion of the apron.

In testimony whereof I affix my signature, in the presence of two witnesses.

WILLIAM JOSEPH GOING.
